UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

PRESSER-LIFTING MECHANISM FOR SEWING MACHINES.

1,420,413.

Specification of Letters Patent. Patented June 20, 1922.

Application filed May 3, 1919. Serial No. 294,393.

To all whom it may concern:

Be it known that I, ALBERT H. DE VOE, a citizen of the United States, residing at Westfield, in the county of Union and State 5 of New Jersey, have invented certain new and useful Improvements in Presser-Lifting Mechanisms for Sewing Machines, of which the following is a specification, reference being had therein to the accompanying drawings.

This invention relates to sewing machines and more particularly to presser-foot lifting mechanism employed therein.

Its primary object is to improve the construction and arrangement thereof so that an operative may raise the presser-foot with her fore-arm or elbow without removing her hand or hands from the work. Also it contemplates an improved construction 15 for supporting the fore-arm of an operative in a manner rendering elevation of the presser-foot easy and still further it comprehends a construction for supporting the fore-arm of an operative in a more natural 20 position than heretofore thereby rendering the daily work less arduous.

Succinctly stated the construction comprises a presser-foot lifting mechanism which may be operated by shifting the fore-arm while resting upon the cloth-plate 25 against a lever fulcrumed on the vertical standard above the cloth-plate and depending downwardly into proximity with the cloth-plate, the lever having a broad face 30 at one end of and adjacent the cloth-plate.

Other objects of the invention will be apparent from the following detailed description of the invention illustrated in the accompanying drawings in which Fig. 1 35 is a front elevation of a sewing machine equipped with the novel presser-lifting mechanism. Figs. 2 and 3 are top and bottom plan views, respectively, of the machine illustrated in Fig. 1. And Figs. 4, 40 and 5 are left- and right-end elevations, respectively, of the machine shown in Fig. 1, parts being broken away in Fig. 5 to better 45 the view.

The invention is applicable to any type 50 of sewing machine and as illustrated is applied to one having a depending head 1 connected on smooth lines to an overhanging arm 2 extending laterally from a vertical standard 3 which is supported by a base- 55 plate 4.

A presser-foot 5, secured to a presser-bar 6 slidably supported in the depending head 1 and having a plate 7 secured to it by screws 8 over a groove 9 in a block 10 on its upper end, is adapted to be lifted 60 through a bellcrank 11 pivoted at 12 below the axis of the overhanging arm and adjacent the junction of the depending head 1 and the overhanging arm 2. The bellcrank 11 has a circularly faced flat end 65 13 which is received within the slot defined by the groove 9 and plate 7 at the upper end of the presser-bar. The opposite end of the bellcrank 11 is pinned at 14 to a link 15 which is articulated at 16 to a rod 17 70 about which is coiled a spring 18 adjustably tensioned between a thrust-collar 19 fixed to the rod 17 and an abutment face 20 inside the overhanging arm. By the thumb-screw 21 the tension of the coiled spring 75 18 may be varied to regulate the yielding pressure with which the presser-foot is urged downwardly upon the work.

A second collar 23 is fixed in spaced relation on the rod 17 from the collar 19 to 80 receive the yoke-end 24 of a second bellcrank-lever 25 fulcrumed at 26 adjacent the junction of the overhanging arm and vertical standard with its opposite end connected by a link 27 to a plural-armed lever 85 28 fulcrumed at 29 in the bed-plate of the machine and connected by a second link 30 which extends vertically upward into proximity with the junction of a vertical standard and overhanging arm where it is connected to the rearwardly extending arm 31 of a sheet-metal lever 32 which is fulcrumed at 33 to a block 34 secured on the front of the vertical standard. The sheet-metal lever 32 is bent at one side to form a stiffening flange 35 which is disposed at an angle to the body of the lever. This lever 32 is shaped at one side to conform to the general outline of the vertical standard and at its lower end has a broad face suitable 95 for operation by one's fore-arm. A projection 36 on the lower end of the sheet-metal lever 32 is adapted to ride over a leaf-spring 37 secured by the screws 38 to the under side and at the rear of the base-plate 4. The leaf-spring 37 is provided with an up-turned lip 39 adjacent an aperture 40 in the frame of the machine and acts as a keeper to hold the presser-foot 100 raised when desired.

The sheet-metal lever 32 is located at one side of a cloth-plate 41 which is provided with a flange 42 extending preferably at an inclination downward from the line of seam-formation. It will be noticed from Fig. 5 that the sheet-metal lever 32 is in line with and at one end of the arm rest constituted by the flange 42. Adjacent the flange 42 the cloth-plate has a vertical face 43.

When the machine is in operation, the presser-foot 5 is yieldingly held down upon the work by the spring 18. When it is desired to raise the presser-foot from the work, which the operator usually manipulates with both of her hands adjacent the stitching point and as contemplated in the present invention with her forearm upon the arm-rest 42, all that she is called upon to do is to press with her fore-arm against the broad face at the lower end of the lever 32 until the projection 36 snaps past the up-turned lip 39 on the spring 37 whereupon the presser-foot will be held in a raised position. In shifting the lower free end of the lever 32 toward the vertical standard the rearwardly extending arm 31 has its end raised thereby pulling upon the link 30, rocking the lever 28, and through the link 25 rocking the bellcrank 25 to pull back upon the link 15 which is connected, through the bellcrank 11, directly to the upper end of the presser-bar 6.

Additional means are also provided for lifting the presser-foot by a foot-treadle or knee-shift. These comprise a rod 44 connected in any suitable manner to a foot-treadle or knee-shift (not shown) and extending to a bellcrank 45 fulcrumed at 46 to the rear of the frame. At its lower end the bellcrank 45 is pinned at 47 to a link 48 which has a forked extremity 49 adapted for one way operation of a pin 50 in a crank-arm 51 fixedly connected to the lever 28. By pulling down upon the rod 44 the pin 50 is moved to the right to effect a turning movement of the lever 28 and consequent elevation of the presser-foot in the same manner as has been described in connection with the fore-arm operable sheet-metal lever 32. The treadle operable lever 45 is also connected to a member 52 which is adapted to operate a strip-guide 53 as described in my copending application Serial No. 294,395 filed on even date herewith.

The bellcrank-lever 25 if desired may be provided with a plurality of wedges as indicated at 54 and 55 for releasing opposed pairs of constant tension devices 56 and 57 in a manner fully disclosed in my pending application Serial No. 149,719, filed February 20, 1917.

Having thus set forth the nature of the invention, what I claim herein is—

65 1. In a sewing machine having a vertical

standard, a presser-foot, a spring for yieldingly holding the presser-foot down upon the work and presser-foot lifting mechanism including a member having a free end movable toward and from the axis of the vertical standard in the general direction of the line of seam-formation and accessible to the operator's fore-arm without necessitating removal of the operator's hands from the work.

75 2. In a sewing machine having a frame including a vertical standard and a cloth-plate, a presser-foot, a spring for yieldingly holding the presser-foot down upon the work and presser-foot lifting mechanism including a lever pivoted on the frame of the machine having a free end located adjacent both the vertical standard and the cloth-plate and movable transversely of the vertical standard in the general direction of the line of seam-formation, said free end being accessible to the operator's arm without necessitating removal of the hands from the work.

80 3. In a sewing machine having a vertical standard, a presser-foot, a spring for yieldingly holding the presser-foot down upon the work, presser-foot lifting mechanism including a member extending along the face of the vertical standard and having a free end disposed at the front of the vertical standard and movable toward and from the same in the general direction of the line of seam-formation.

85 4. In a sewing machine having a vertical standard and cloth-plate, a presser-foot, a spring for yieldingly holding the presser-foot down upon the work and presser-foot lifting mechanism including a member fulcrumed on an axis extending substantially lengthwise of the machine, and having a depending free end located near the vertical standard and cloth-plate and extending into a position wherein it is easily accessible so that it may be shifted by the operator during normal operation of the machine.

90 5. In a sewing machine having a vertical standard and a cloth-plate, a presser-foot, a spring for yieldingly holding the presser-foot down upon the work and presser-foot lifting mechanism including a member having a free end located adjacent the cloth-plate and the vertical standard and shiftable substantially horizontally for permitting the presser-foot to be raised.

95 6. In a sewing machine having a cloth-plate, a presser-foot, a spring for yieldingly holding the presser-foot down upon the work, and presser-foot lifting mechanism including a sheet-metal lever having an end freely movable in the general direction of the line of seam formation and with a relatively broad face adjacent the cloth-plate and convenient for operation by the fore-arm.

7. In a sewing machine having a vertical standard, a presser-foot, a spring for yieldingly holding the presser-foot down upon the work, a presser-foot lifting mechanism including a sheet-metal lever having a broad face convenient for fore-arm manipulation and a stiffening flange disposed at an angle to said broad face, said lever being disposed adjacent and extending in the same general direction as the vertical standard.
8. In a sewing machine having a vertical standard, in combination, a cloth-plate flanged lengthwise at its front portion, a presser-foot, a spring for yieldingly holding the presser-foot down upon the work, presser foot lifting mechanism including a lever arranged for fore-arm operation and located at one end of the flanged portion of the cloth-plate.
9. In a sewing machine having stitch-forming mechanism, in combination, a cloth-plate flanged at an inclination downward and laterally of the line of seam-formation, a presser-foot, a spring for yieldingly holding the presser-foot down upon the work, presser-foot lifting mechanism including a member having a free shiftable end located in line with and at one end of the flanged portion of the cloth-plate.
10. In a presser-foot lifting mechanism, in combination, a presser-foot, an arm-rest, a member located at one end of the arm-rest and having a free end movable transversely of the arm-rest, and connections between said member and said presser-foot for lifting the latter by movement of the former without requiring the operator to lift her fore-arm from its rest.
11. In a sewing machine having a cloth-
- plate an overhanging arm and a vertical standard, in combination, a presser-foot, a spring for yieldingly holding the presser-foot down upon the work, a lever pivotally supported nearer to the junction of the vertical standard and overhanging arm than to the cloth-plate and transverse to the general direction of the feed of the work and depending downwardly to a point adjacent the cloth-plate and adapted to be operated by substantially horizontal movement of one's fore-arm while resting upon the cloth-plate.
12. In a presser-foot lifting mechanism, in combination, a presser-foot, an arm-rest, a member located at one end of the arm-rest and having a free end movable transversely of the arm-rest, and connections between said member and said presser-foot for lifting the latter by movement of the former without requiring the operator to lift her fore-arm from its rest, and a spring-keeper located adjacent the free end of the member for holding the presser-foot in a raised position.
13. Presser-foot lifting mechanism for sewing machines having an overhanging arm and a vertical standard comprising a presser-foot, levers at the opposite ends of the overhanging arm, a member operatively connecting said levers, a third lever pivoted to the vertical standard and having a free end accessible for fore-arm manipulation, and connections between said third lever and said first mentioned levers for permitting the presser-foot to be lifted by movement of the fore-arm.

In testimony whereof, I have signed my name to this specification.

ALBERT H. DE VOE.
